UNITED STATES PATENT OFFICE.

ROBERT WILLIAM SILVERSIDES, OF MALTON, ENGLAND.

RUG AND CARPET MAKING MACHINE.

1,135,408.

Specification of Letters Patent. Patented Apr. 13, 1915.

Application filed January 25, 1913. Serial No. 744,217.

To all whom it may concern:

Be it known that I, ROBERT WILLIAM SILVERSIDES, formerly residing at 100 Grange Terrace, Wood street, Norton, Malton, in the county of York, England, but now of 14 St. Paul's Terrace, Norton, Malton, in the county of York, England, have invented new and useful Improvements in or Relating to Rug and Carpet Making Machines, 10 of which the following is a specification.

This invention relates to improvements in rug and carpet making machines of the type in which strips or tabs of cloth are fed to, and passed through, a canvas or other woven sheeting which forms the back or foundation of the rug or carpet, and in which tabs or strips of cloth are secured; and it particularly refers to that class of machine in which a number of needles are 20 mounted upon a horizontal bar to which a vertical intermittent reciprocating motion is imparted by means of cams and levers from some rotating part of the machine.

The object of this invention is to produce 25 a machine of high efficiency as regards the work performed in a given time, and which consists in providing means for drawing a number of strips or tabs of cloth simultaneously through a double fold of the canvas or other woven sheet or backing, the said 30 canvas being clamped on to the perforated or recessed wings or arms of an intermittently rotating roller, the strips or tabs of cloth having been previously placed on an 35 inclined board from which they are pressed on to the pins of a traveling lag or sheet mounted upon endless chains by which they are conveyed to a number of springs or clips mounted upon the inner ends of a number 40 of slotted bars or levers connected together in a lazy-tong arrangement so as to bring the clips or tabs of cloth into position to be seized and held by the needles which are also arranged to form jaws for drawing the tabs or strips through the double folds of the 45 canvas backing.

This invention consists in the details of construction and combination of the parts hereinafter described and claimed.

In the drawings hereunto annexed I have shown a method for carrying the invention into effect, in which—

Figure 1 is a part side elevation of the machine with the needles open in the lowest position and with the clips or springs in

position for receiving the strips or tabs of cloth from the pins of the traveling lag sheet; Fig. 2, is a plan looking at the top of Fig. 1; Fig. 3, is a part section on line A, A, Fig. 2; Fig. 4, is a side elevation of the portion of the machine shown at Fig. 1 with the needles open at the upper portion of their stroke, and the springs or clips in position for delivering the strips or tabs of cloth to the needles; Fig. 5, is a part side elevation of the framework of the machine, and of the inclined board upon which the strips or tabs of cloth are arranged for placing them on the traveling lag sheet; Fig. 6, is an end elevation of Fig. 5; Fig. 7, is a 70 plan of same; Fig. 8, is a part sectional elevation of the inclined board shown at Fig. 5 with the tab pressing device in an open position; Fig. 9, is a part sectional elevation of the inclined board shown at Fig. 5 with the tab pressing device closed, and with a strip or tab of cloth pressed on to the needles of the traveling lag sheet; Fig. 10, is a part elevation of the mechanism for opening and closing the tab pressing device; Fig. 11, is 80 a plan of same; Fig. 12, is a part elevation of a portion of the machine showing the needles in their open and closed positions together with the canvas clamping device closed, and means for clearing the tabs 85 from the path of the needles; Fig. 13, is a part elevation of winged roller and of the clamping device open; Fig. 14, is an elevation of a needle closed; Fig. 15, is an end elevation of the same; Fig. 16, is an end elevation drawn at the opposite side of Fig. 14; Fig. 17, is a diagrammatic view showing the 90 position of the cam and levers for opening the needle when the latter is at the top of its stroke; Fig. 18, is a diagrammatic view showing the mechanism for rotating the winged roller; Fig. 19, is a diagrammatic view showing the lever mechanism for operating the clearing rod; Fig. 20, is a diagrammatic view showing the cam and levers for raising and lowering the needle bar; Fig. 21, is an elevation of the cam for raising and lowering the needles; Fig. 22, is a sectional elevation of the same on line B, B, Fig. 21; Fig. 23, is an elevation of the cam for operating the winged roller, the clamping jaws, and the tab clearing bar; Fig. 24, is a sectional elevation of the same on line C, C, Fig. 23; Fig. 25, is a sectional elevation of the lags with pins attached thereto; 100 105 110

Fig. 26. is a plan looking underneath; Fig. 27. is a part plan of the canvas after the tabs or strips of cloth have been inserted.

Like parts in all the views are marked 5 with similar letters of reference.

The framework of the machine comprises the standards *a*, *a* slotted at *d*, bed *b*, stays *c*, *c*, and a pair of standards *f* mounted upon the bed *b*. In the slots *d* a bar *e* is made to 10 intermittently reciprocate, and a spindle *g* upon which are mounted sprocket wheels *h* is made to intermittently rotate in the bearings of the standards *f*. In some cases the standards *f* may be arranged to form a part 15 of the framework of the machine, but for convenience in construction and adjustment they are shown mounted separately upon the bed of the machine. Bearings are also provided for the various shafts to be hereinafter described in the standards *a*.

i is the driving shaft of the machine upon which are mounted the fly wheel *j*, cams *k* and *l*, eccentric *m* and crank *n*.

The machine may be driven either manually, as illustrated, by means of the lever *o* and the handle *p* mounted on the shaft *i*, or by any suitable power means substituted in lieu thereof.

The slotted portion *d* of each standard *a* 30 forms a vertical slide in which is arranged to work a flange or other block *q* adapted to receive the ends of the needle bar *e*. The needle bar *e* is made for the greater part of its length rectangular in cross section and provided with enlarged ends,— 35 which are circular in cross section,—and the outer ends of the needle bar are reduced in diameter so as to pass into, and be secured in the blocks *q*.

An intermittent reciprocating motion is 40 imparted to the needle bar *e*,—as shown at Figs. 3 and 20,—by means of the cam *l* through bowl or runner *r*,—which works in the cam path *l*¹,—carried by a pin on the pendant lever *s* mounted upon the rocking shaft *t*. To the rocking shaft *t* are also 45 fixed a pair of levers *u* arranged respectively at suitable distances from the end of the rocking shaft. The inner ends of the 50 levers *u* are jointed to levers *v* mounted upon the reduced ends of the needle bar. As the driving shaft *i* rotates the cam *l* causes the needle bar to be raised and lowered as the bowl or runner works in the path 55 *l*¹ of the cam. To the upper surface of the needle bar *e* are fixed at suitable distances apart a number of vertical bifurcated supports *w* to which the needles are jointed. The vertical supports for the needles are 60 arranged at suitable distance apart to correspond with the center of the distance between each of the strips or tabs of cloth *x* which are inserted, as shown at Fig. 27, in the canvas backing *y*. The tabs of cloth *x* 65 are inserted in rows in said backing.

Each needle consists of two portions *z* and *z*¹,—as shown at Figs. 1, 3, 14 to 17,—which are pivoted at *l* to the supports *w* in a similar manner to a pair of scissors. The portion *z* of each needle is longer than 70 the portion *z*¹, and the longer or projecting part is made to form a point for piercing through the canvas or other backing *y*. The lower part of each of the portions *z* and *z*¹ of each needle is curved outward, 75 as shown at 2 and 3 of Figs. 14 and 17. The lower curved end portions of each needle are connected together by rods 4 and 5. The rods 4 and 5 extend across the machine between the standards *a*, and are provided on each of their outer ends with bowls or runners 6, 7, 8 and 9 which work against the vertical cam paths 10, and 11, as shown at Figs. 1, 3, 12 and 13, which are employed 80 for opening the needles when they are at the lowest portion of their stroke. It will readily be understood that a pair of cam paths 10 and 11 are provided upon each standard *a*. When the runners 6, 7, 8 and 9 pass off the cam paths 10 and 11 the needles are closed by means of the spring 12, the ends of which are connected to the lower parts of the curved portions 2 and 3. When 85 the needles have been raised by the cam and levers as hereinbefore mentioned and described,—as at Fig. 20,—they are opened by the lever mechanism shown in diagrammatic view at Fig. 17. That is to say, on the fly wheel *j* is provided and fixed a cam 13 which engages with a runner 14 mounted upon a lever 15 fixed upon a shaft 16. On the shaft 16 are two or more levers 17 which are connected by link 18 to bell-crank lever 19, which is fulcrumed at 20 to the pendant portion or bracket 21, fixed to, or carried by, 90 needle bar *e*. To the lower arm of the bell-crank lever 19 is jointed a link 22, the upper end of which is connected to an arm of an inverted bell-crank lever 23; the other arm of the bell-crank lever 23 is connected by link 24 to the rod 4 which passes through the curved portions 2 of the needle. The curved portions 3 of the needle are connected to the upper end of the arm of 95 curved lever 19 by means of link 25, the opposite end of which is connected to rod 5. By this means it will readily be seen that when the cam 13 operates bowl or runner 14 and the lever mechanism connected therewith, the two portions *z* and *z*¹ of the needle will be operated for opening the needle as shown at Fig. 17. The two rods 4 and 5 are connected together by a number 100 of springs 28 (Fig. 17) which are employed for closing the needle as soon as the roller passes off the cam 13.

Although only one set of levers and links 17 to 25 are shown it will readily be understood that additional sets may be employed as circumstances require.

Above the slots *d* which form a vertical slide is mounted in suitable bearings on the standards *a* a roller provided with, say, four, 5 arms or wings, or webs 27 to which an intermittent rotary motion is imparted by lever and pawl mechanism as shown in the diagrammatic view at Fig. 18, actuated by cam *k* (Figs. 13 and 23) through runner 29 mounted on lever 30 fixed to shaft 31. On 10 the shaft 31 is fixed a lever 32 (Fig. 18), the outer end of which is connected by rod 33 to the short arm of bell-crank lever 34. The last named bell-crank lever is mounted upon a shaft 35, and this long and curved 15 arm is connected to the slotted lever 36, the lower end of which is jointed to the bell-crank lever 37 which is fulcrumed upon the spindle or trunnion 38 of the winged roller. On one or both ends of the spindle or trunnion 38 is provided a ratchet wheel 39 and 20 a disk 40. In the ratchet wheel are provided a number, say, four, of teeth 41 with which the pawl 42 is made to engage. The pawl is jointed to the outer end of lever 37, 25 and it is kept to its work by means of spring 43. In the disk 40 are formed a number, say, four, of recesses 44 with which a stop pin 45 is made to engage. The stop pin is mounted upon a double ended lever or shoe 30 46 which is fulcrumed at 47 to a bracket 48 (Fig. 4). The sole or plate of the shoe 46 is acted upon when it is desired to withdraw the pin 45 from a recess 44 by the short arm 49 of the double ended lever 37; a spring 50 35 is attached to the shorter end of the shoe 46 for keeping the pin 45 within the recess when not acted upon by the short arm of the bell-crank lever 37. The canvas *y* is made to pass over three of the four wings 27 as 40 shown at Fig. 12, and when in this position two of the wings will be in a vertical position and two in a horizontal position and the canvas is closed upon one of the horizontal wings 27 by means of the jaws 51 and 52 (Figs. 12 and 13). The jaws 51 and 45 52 consist of a pair of plates which are fixed respectively to a number, say, four, of levers 53 and 54 which are fulcrumed upon the rod 35. The levers 53 are shown at Fig. 13 in 50 the form of a bell-crank lever, and each lever 53 and 54 is connected respectively by a rod 55, 56 to a pair of levers 57 and 58 arranged one behind the other fixed to the shaft 31 which is operated by cam *k*. The wings 27 55 and the jaws 51 and 52 are perforated or recessed at suitable distances apart to permit of the passage of the needles through the canvas and for the canvas to be readily traversed along as occasion requires. The canvas 60 65 in its passage to the wings 27 passes over a roller *c* which may be mounted upon stay *c*¹ and from thence it passes,—as shown at Fig. 3,—to the wings 27 and after receiving a tab or strip of cloth it is conveyed to a number of rollers 59 and 60 mounted in a

frame 61 which is carried at its upper end by the stay *c*¹. The rollers 59 and 60 may be of the same or different diameters. In the drawings roller 59 is shown larger than the rollers 60 and it is provided with a recess 62 70 which is slightly narrower than the width of the canvas backing *y* in order to enable the inserted tabs to pass readily over it.

The tabs *x* which form the pile of the rug or carpet, are of any predetermined length, 75 width and color, and are cut to size and arranged upon an inclined board 63 (Figs. 5 to 11). The tabs or clips of cloth *x* are arranged in position upon the board 63, which is divided into a number of compartments 80 by vertical projections 64 which only extend for a short distance from the front edge 65 of the board 63. The projections 64 are arranged at such a distance or pitch apart that the tabs can be readily passed between 85 them. Between each vertical projection 64 is also formed a recess 66 for the passage of the pins on the lags to be hereinafter described. The tabs to be employed in the rug or carpet making are arranged on the face of 90 the inclined board 63 and are retained thereon by the projecting battens 67. The board or table 63 is retained in position both as regards the standards *a* and the angle of inclination by the brackets 68 which are fixed to 95 the hereinbefore described standards *f* which carry the spindle *g* and sprocket wheel *h*.

To the front edge 65 of the table or board 63 is jointed a second angular board 69 which forms a stop for the tabs. On the inner face of the angular stop 69 are formed a number of grooves or recesses for the pins of the lags. The recesses or grooves 70 are at the same pitch as, and corresponding in 100 position with, the grooves 66.

An intermittent tilting motion is imparted to the angular stop board 69 by means of a pair of levers 71 and 72 connected together by a hand bar or rod 73. The levers 71 and 72 are fulcrumed upon pins 74 carried by 110 the guide pieces 75 and pendant brackets 76. The inner end of levers 71 and 72 are jointed to the spindle 77 which carries the sprocket wheels 78 and 79, around which the endless chains 80 are arranged to pass. The spindle 115 77 is arranged to work in the slots 81 of the brackets 76, and the spindle is connected by bifurcated levers 82 with levers 83 fulcrumed at 84 to the pendant brackets 76. The free end of each lever 83 is connected by a second 120 bifurcated lever 85 and pin 86 to the outer end of the angular stop board 69. The angular stop board is pivoted at 87 to brackets 88 fixed to the inclined board of table 63. As the spindle 77 is raised by the downward 125 movement of the levers 71, 72 an upward movement is imparted to levers 83 and 85 for turning the inner end of the angular stop board 69 from the position shown at Fig. 8 into that shown at Figs. 9 and 10. 130

When the angular stop board is turned into the position shown at Figs. 9 and 10 it will press a tab α on to the pins 89, mounted on the top of the lags 90, which are fixed at 5 suitable distances apart upon the endless traveling chains 80. When the levers 71, 72 are in the raised position shown at Fig. 5, that is, with the spindle 77 at the bottom of the slots 81, then the sprocket wheels 78, 10 79 will have been withdrawn to their lowest position for enabling the tabs to pass down and through the recesses 66 so as to be conveyed into the position to be received by the spring clips 91 formed on the ends of 15 levers 92.

The lags 90 are shaped in cross section as shown at Fig. 25 so that their reduced upper portion and the pins 89 thereon will pass into each spring clip. The spring clips 91 20 are shaped as shown at Figs. 3 and 4 and are made to fit the upper reduced portion of the lags 90. A part of the spring clip is cut away so as to permit of the pins 89 passing through and clear of the spring clip.

25 The strips or tabs of cloth α when received from the inclined board of table 63 are in a flat condition, as shown in dotted lines at Figs. 3 and 4, and after the spring clips 91 have passed on to them, as shown at Fig. 3, 30 they assume the curved or U-shaped form shown in dotted lines at Fig. 25. The spring clips 91 are made of such a strength as to hold a tab or strip of cloth in its curved or U-shaped position and withdraw it from the pins 89 and to carry it into the position shown at Fig. 4 so that its end may be received and passed between the scissor like jaw portions of the needles. The spring clips are attached to the upper ends of a number 35 of levers 92 which are mounted upon a rod or spindle 93 carried by two or more levers 94 which are fulcrumed to the standards α at 40 95. Each lever 92 is bifurcated at 96 at its inner and lower ends, and the said levers are connected together at or about their centers, and also at their bifurcated ends respectively by means of the slotted plates 97, 98. The levers 92 are also jointed or connected to a lazy-tong arrangement of levers 45 99, as shown at Fig. 2. In order to open and close the lazy-tong arrangement of levers 99 their opposite ends are connected to the projections 100, 101, and the bosses 102, 103 which slide upon the rod or spindle 93.

50 In the periphery of the bosses 102, 103 is formed an annular groove or recess 104, 105, in which the bifurcated or hooked end of levers 106, 107 are made to work for expanding or contracting the lazy-tong arrangement of levers 99 for regulating the position of the spring clips with regard to the lags 90 and pins 89, and also with the pointed needles which simultaneously pass through the double layer of canvas when it is clamped 55 upon a wing, or web 27. The levers 106, 107

are fulcrumed to the cross bar 108 which is fixed at its respective ends to the levers 94 so as to move therewith.

On the inner and curved ends of the levers 106, 107 is respectively mounted a bowl or 70 runner 109, 110. The bowls or runners 109, 110 are arranged to work within the inverted trough shaped cam paths 111, 112 which are fixed to the bed plate b of the machine at or about the angle shown at Fig. 2. These 75 cam paths are made in the form shown and have slots or openings in their upper sides through each of which one of the levers 106, 107, passes, the bowls or runners on the inner ends of said levers working against 80 the inner surface of the cam paths.

The required intermittent oscillating movement for moving the levers 94 and 92 and spring clips 91 into the position shown at Figs. 3 and 4 is imparted by means of 85 the eccentric m mounted upon the driving shaft i . The strap m^1 of the eccentric is connected to a curved bifurcated lever 113, the upper end of which is attached to a lever 114 which is fixed to the rod or spindle 90 95 upon which the levers 94 are mounted. As the eccentric revolves, and when at or about its upper stroke, it will have caused the levers to have traveled from the position shown at Fig. 3 to that shown at Fig. 4. 95 Simultaneously with this movement of the levers 94 the lazy-tong arrangement of levers are closed from the open position shown at Fig. 2 into a position for delivering the tabs or strips of cloth α to the jaws 100 of the vertical reciprocating needles, which will then have passed through a double layer of the canvas, and have been opened as shown at Fig. 4. Simultaneously with 105 this motion for actuating the levers 94 the levers 92 are caused to turn on the rod 93 for reversing their position by means of the lower ends of the lazy-tong arrangement of levers 99 having a central fixing 115 and secured thereto, to which is jointed the 110 curved rod 116. The opposite end of the curved rod is provided with a bifurcated end 117 to which is jointed a curved lever 118 provided with bifurcated ends; the upper bifurcated end of lever 118 is connected 115 to a lever 119 mounted loosely upon spindle 31, owing to the movement for turning over the said levers being quicker than the movement required for oscillating the levers 94. The lower bifurcated end of the curved lever 120 118 is connected to the pin or bolt 120 which attaches the bifurcated end 113 and lever 114 together. During the movement of the levers 94 from the position shown at Fig. 3 to the closed position shown at Fig. 4 the levers 106, 107 pivotally carried by said levers 94 are rocked on their fulcrums by the cam paths 111, 112, and their outer ends caused to approach each other, thus partly 125 collapsing the lazy-tong arrangement of 130

levers 99 and moving spring clips 91 on the levers 92 closer together and in line with the vertically reciprocating needles z , z' .

An intermittent rotary motion is imparted to the sprocket wheel h from the crank n mounted upon the driving shaft i . The crank is connected by rod 121 to a bell-crank lever 122 fulcrumed to a bracket 123^x fixed to one of the standards a . One arm of the bell-crank lever 122 is connected by a rod 123 with a second bell-crank lever 124 which is also bifurcated so as to permit of a ratchet wheel 125 and stop wheel 126 working between it. The bifurcated bell-crank lever 124 is mounted loosely upon spindle g while the ratchet wheel 125 and stop wheel 126 are keyed or otherwise fixed on the same spindle as the sprocket wheel h . To the bell-crank lever 124 is also jointed between its bifurcations a pawl 127 which engages with the ratchet wheel 125 when it is required to intermittently rotate the sprocket wheel h . The pawl 127 is retained to its work by spring 128. Below the stop wheel 126 is fulcrumed a lever 129 in the form of a shoe and to this lever is fixed a stop pin 130 which enters a recess 131 of the stop wheel for retaining the sprocket wheel and lag 90 in position for the removal of the tab or strip of cloth α by a spring clip 91. The stop pin 130 is moved out of position by the short arm of the bifurcated lever 124 coming in contact with the sole plate 132 of lever 129. The stop pin 130 is retained in position within a recess 131 by means of a coiled spring 133, one end of which is attached as at Fig. 3 to the lever 129, and the opposite end to the standard f .

After the tabs α have been inserted in the canvas or other woven backing y in rows, as shown at Fig. 27 the tabs require,—after the needles have descended to their lowest position,—to be moved out of position so that the needles on their next upward stroke will not come in contact with the tabs in the previously inserted rows. To accomplish this a rail or rod 134 is mounted in a pair of double ended levers 135 (Figs. 3 and 19) fulcrumed on a rod 136, one end of which is fixed to the standard a and at the other end to a bracket 137 which is fixed to the second standard. The bracket 137, shown in dotted lines at Fig. 19, is provided in order to permit of the movement of the slotted lever 36. The upper portions of the curved levers 135 are connected together by a second rod or bar 138 and a connection is made between the rod 138 and a bell-crank lever 139,—mounted upon shaft or spindle 35,—by a rod or bar 140. The shorter arm of bell-crank lever 139 is connected to a lever 141 mounted upon shaft or spindle 31 by a rod or bar 142. The requisite motion is imparted to rod or spindle 31 from cam k as previously explained. When the needles are

passing through the double layer of canvas clamped on to one of the wings 27 the clearing rod 134 will be in the position shown at Fig. 12, but when the jaws 51, 52 are opened to their widest position, as shown at Fig. 13, 70 and the spring clips 91 and levers 92 being about midway between the positions shown at Figs. 3 and 4, and also in or about a vertical position prior to being turned over for delivering the tab to the needles, then the 75 clearing rod 134 will be in the position shown at Fig. 13.

The action of the apparatus is as follows:—The tabs or strips of cloth α , which form the pile of the rug or the carpet, are 30 first placed upon the table 63 and arranged by the operator into the spaces between the vertical projections 64 at the front and lower edge of the table or board 63. After the operator has arranged by hand the tabs 85 or strips of cloth α as just described, the hand rail 73 is depressed in the direction of arrow shown at Fig. 5, for raising the sprocket wheel 78, 79 and lags 90,—which are fixed to the endless chains 80,—and pins 90 89 so that they will pass into the recess 66 in the board or table 63. Simultaneously with the raising of the sprocket wheel 78, 79, the angular stop 69 is turned over into the position shown at Figs. 9 and 10 for 95 pressing the tabs or strips of cloth α on to the pins 89. After this has been done the sprocket wheel 78, 79 is returned to the original position shown at Fig. 5. A rotary motion is imparted to the driving shaft i 100 either by hand or power and the spring clips 91 having been moved into the position shown at Fig. 3 receive the tabs and withdraw them from the pins when the lags 90 have been caused to travel from the front of 105 the bar into the position shown at Fig. 3. The required intermittent motion for causing the endless chains 80 to travel is imparted by the ratchet mechanism previously described. The levers 92 with a tab in each of the 110 spring clips 91 are then caused to travel by the means previously described into the position shown at Fig. 4, during which movement of the levers 92 and 94 the position of the spring clips will first have 115 imparted to them the oscillating movement for closing the clips closer together so as to be of the same pitch as the vertical reciprocating needles, and they are also turned over so as to deliver the tabs or strips α to the 120 scissor like jaws of the said needles. When the spring clips 91 are in the position shown at Fig. 3, for receiving the strips or tabs α from the lags 90, the vertical reciprocating needles will then be at the bottom of their 125 stroke with their jaws open,—as shown at Fig. 3,—and the clamping jaws 51, 52 open, as shown at Fig. 13. During the movement of the spring clips 91 from the position shown at Fig. 3 to that shown at Fig. 4 the 130

needle bar is raised and the runners 6, 7, 8 and 9 will then pass in their upward position out of contact with the cam paths 10, 11 for closing the jaws of the needle. Simultaneously with this upward movement of the needles the jaws 51, 52 will have been closed upon the canvas with one of the wings 27 between two layers of canvas so that by the continued upward movement of the needles with their jaws closed they pass through the perforations or recesses in both the jaws 51, 52 and of the wing 27 and also through the two layers of the backing y . As soon as the needles reach the highest point of their upward stroke they are again opened,—by the means previously described,—in order to receive the tabs or strips of cloth x which form the pile of the rug or carpet. On the descent of the needles the said tabs or strips are drawn through the two layers of the backing and when the said tabs or strips have been drawn about half their length the needles are again caused to open by the said runners coming in contact with the cam paths 10, 11, and the tabs are left in that position by the needles. During the descent of the needles the spring clips are again moved into their outward position, and during such movement the clearance bar 134 is moved into the position shown at Fig. 3 for removing the row of tabs x just inserted in the backing y clear of the needles when they are again caused to ascend and the jaws 51, 52 are then again opened and the wings 27 rotated so as to bring another wing into position, the perforations or recesses in the jaws 51, 52 and wings 27 permitting of the free movement and clearance of the inserted tabs x . The outer end of the backing y may be weighted for drawing it over the rollers 59, 60, and when the backing is thus drawn forward the two free ends of each tab x will be on the same and underside of the backing and hung down in the position shown at Fig. 3. The backing y being held by a weight or other means is caused to travel forward with each intermittent rotation of the wings 27. The fold of the backing over the wing will, by means of the same weight, be straightened or drawn smooth and the tabs, each drawn by a needle through perforations in the fold will assume a looped position shown in Fig. 3, the reverse side of the backing or canvas when the rug is finished presenting the appearance illustrated in Fig. 27.

The cycle of operations for conveying the tabs to the needles and inserting them in the backing may be repeated until a rug or carpet of the required size has been made.

It will readily be understood that the number of intermittent vertical reciprocating needles and spring clips will be varied in accordance with the width or number of tabs to be inserted. In the drawings at Fig. 2

nine needles are shown by way of example only, but I wish it to be distinctly understood that their number may be increased as circumstances require. Also that the number of partitions and width of the board 70 will require to be correspondingly varied.

What I claim is:—

1. In a machine of the character described, folding mechanism for producing a fold in the foundation of a rug, carpet, or the like, a single gripping needle having a point in the form of a separable jaw, means for causing said needle to pass emptily and in closed position in a transverse direction through both thicknesses of said fold and to return the same, and means for first opening said jaw after passing through the fold to receive a tab and then closing the jaw to grip said tab that it may be drawn through the fold on the return of the needle. 85

2. In a machine of the character described, folding mechanism for producing a fold across the entire width of the foundation of a rug, carpet, or the like, a plurality of gripping needles each having its point in the form of a separable jaw, means for causing said needles to pass simultaneously and emptily with closed jaws in a transverse direction through both thicknesses of said fold and to return the same, and means for first opening said jaws after passing through the fold to permit each to receive a tab, and then closing said jaws to grip the tabs that they may be drawn through the fold on the return of the needles. 95

3. In a machine of the character described, folding mechanism for producing a fold across the entire width of the foundation of a rug, carpet or the like, a plurality of gripping needles each having its point in the form of a separable jaw, means for causing said needles to pass simultaneously and emptily with closed jaws in a transverse direction through both thicknesses of said fold and to return the same, means for first opening said jaws after passing through the fold to permit each to receive a tab, and then closing the jaws to grip the tabs that they may be drawn through the fold on the return of the needles, and a plurality of devices for conveying individual tabs in said needles. 105

4. In a machine of the character described, folding mechanism for producing a fold in the foundation of a rug, carpet or the like, a plurality of gripping needles each having its point in the form of a separable jaw, means for causing said needles to pass simultaneously and emptily with closed jaws in a transverse direction through both thicknesses of said fold and to return the same, means for first opening said jaws after passing through the fold to permit each to receive a tab and then closing said jaws to grip the tabs that they may be drawn through the fold on the return of the needles. 120

needles, a plurality of devices for conveying individual tabs to said needles, and means for causing said devices to move laterally from one another when traveling from the needles, and toward one another when approaching the needles.

5. In a machine of the character described, folding mechanism for producing a fold in the foundation of a rug, carpet or 10 the like, a plurality of gripping needles each having its point in the form of a separable jaw, means for causing said needles to pass simultaneously and emptily with closed jaws in a transverse direction through both thicknesses of said fold and to return the same, means for first opening said jaws after passing through the fold to permit each to receive a tab, and then closing the jaws to grip the tabs that they may be drawn 15 through the fold on the return of the needles, a plurality of devices for conveying individual tabs to said needles, and other means for delivering tabs one at a time to said devices.

25. 6. A machine for making rugs in which strips or tabs of cloth are fed to and passed through folds of a foundation canvas comprising a framework, a vertical reciprocating bar, needles formed in three parts, two 30 of which parts are jointed to a third and supporting part fixed to said bar, a winged roller mounted above said needles, levers jointed to said framework and provided with spring clips for conveying tabs of cloth to the needles, rollers for receiving the 35 foundation canvas in which the tabs are inserted, and means for actuating the said bar, needles, levers, and rollers.

7. In a machine in which strips or tabs of 40 cloth are fed to and passed through folds of a foundation canvas the combination of a framework, a reciprocating bar and means for actuating the same, a plurality of vertical supports fixed to said bar, a pair 45 of jaws jointed scissor-like to each vertical support, one of said jaws being longer than the other, pointed at its upper end for piercing the foundation canvas of the rug and having a stepped and reduced portion 50 below its pointed end into which the end of the shorter jaw passes, and means for opening and closing the said jaws.

8. In a machine in which strips or tabs of 55 cloth are fed to and passed through folds of a foundation canvas the combination of a framework having vertical slots formed therein, slide blocks mounted in the said 60 slots, a horizontal bar mounted by its ends in the slide blocks, means for imparting an intermittent vertical motion to the bar, a plurality of vertical supports fixed to the upper surface of the horizontal bar at equal distances apart, a pair of jaws jointed scissor-like to each vertical support, the two 65 jaws being of different lengths, the longer

one being pointed for piercing purposes and reduced in thickness at a distance from its pointed end to form a recess for the reception of the shorter jaw, and means for opening and closing the jaws.

70

9. In a machine in which strips or tabs of cloth are fed to and passed through folds of a foundation canvas the combination of a framework having vertical slots formed therein, cam paths formed at the lower ends 75 of the slots, a horizontal bar intermittently reciprocating in the vertical slots, a plurality of eyeless pointed needles mounted scissor-like on the horizontal bar at equal distances apart for piercing the foundation 80 canvas of the rug and drawing a tab of cloth through its folds, each of the needles comprising a vertical support fixed to the said horizontal bar and a pair of jaws jointed to said support, one of the jaws being 85 longer than the other, pointed at its upper end and reduced in thickness to form a recess for the reception of the upper end of the shorter jaw whereby a clamp is formed for drawing a tab of cloth through the 90 folds of the foundation canvas, the lower ends of each jaw being curved outward, rods for connecting the whole of the lower end of the jaws together, lever and spring connections whereby the whole of the jaws are 95 simultaneously opened and closed, and cams for operating said levers.

10. In a machine in which strips or tabs of cloth are fed to and passed through folds of a foundation canvas the combination of 100 slotted framework having cam paths arranged at the bottom of the slots, blocks sliding in the slots, a horizontal bar mounted by its ends in the said blocks, means for vertically reciprocating the bar, a plurality 105 of eyeless pointed needles mounted vertically upon the said bar at equal distances apart, each needle being formed of two jaws of different lengths, supports to which the jaws of the needles are jointed, means for opening and closing the jaws of the needles, a winged rotating roller carrying the foundation 110 canvas and arranged above the slots in the framework, the wings being recessed for the passage of the needles, means for intermittently rotating the winged roller, a pair of jaws for clamping the foundation canvas on to the winged roller during the stroke of the needles, said jaws having a plurality of holes formed therein, and means for opening and closing the clamping 115 jaws.

11. In a machine in which strips or tabs of cloth are fed to and passed through folds of a foundation canvas the combination of a 120 slotted framework having cam paths at the bottom of the slots, an intermittently rotating winged roller carrying the foundation canvas, each wing having a plurality of recesses formed therein, a pair of clamping 125 jaws.

130

jaws jointed to the framework, means for opening and closing said jaws on to the wings, said jaws having a plurality of perforations therein, a reciprocating bar, a plurality of eyeless pointed needles having scissor-like jaws mounted vertically upon the said bar, and means for vertically and intermittently reciprocating the same.

12. In a machine in which strips or tabs of cloth are fed to and passed through folds of a foundation canvas the combination of the slotted framework having cam paths at the bottom of the slots, an intermittently rotating winged roller having a plurality of recesses in each wing, a ratchet wheel mounted upon the spindle of the said roller, a spring controlled double ended lever mounted upon said spindle, a pawl, a slotted lever and a spring jointed to the free end of the lever, a lever and rod connection with the slotted lever, a shoe provided with a stop pin, and pivoted to the framework, said shoe being operated by one of the arms of the double ended lever, a disk mounted on the spindle of the winged roller, said disk having recesses in its periphery into which the stop pin enters for arresting the rotation of the roller, a plurality of needles for drawing tabs through folds in said foundation, and means for feeding tabs to the needles.

13. In a machine in which strips or tabs of cloth are fed to and passed through folds of a foundation canvas, the combination of a slotted framework having cam paths at the bottom of the slots, blocks sliding in the slots, a horizontal bar mounted by its ends in said blocks, means for intermittently reciprocating the same, a plurality of eyeless pointed needles provided with scissor-like jaws for receiving and inserting tabs of cloth in folds of the canvas, supports fixed to the horizontal bar to which the needle jaws are jointed, means for intermittently opening and closing the needle jaws, an intermittently rotating winged roller carrying the foundation canvas having recesses formed in each wing, said recesses corresponding in number with the needles, means for operating the winged roller, a pair of perforated jaws, a rod fixed to the framework on which are jointed the perforated jaws for clamping a double fold of the canvas on to each flat surface of a wing, means for opening and closing the jaws, an intermittently reciprocating clearing bar for removing the ends of the tabs of cloth out of the path of the needle, and means for operating the said clearing bar.

14. In a machine in which strips or tabs of cloth are fed to and passed through folds of a foundation canvas the combination of a framework having vertical slots therein with cam paths at the bottom of the same, a horizontal bar intermittently reciprocating in the said slots, a plurality of eyeless pointed

needles with jaws for holding and inserting tabs of cloth in folds of the canvas, vertical supports to which the needle jaws are jointed, means for reciprocating the bar and for opening and closing the needle jaws, a winged roller for carrying the foundation canvas and having a plurality of recesses in each wing, means for intermittently rotating the winged roller, rollers upon which the foundation canvas is mounted, means for intermittently traversing the same, a rod carried in bearings on the framework, perforated clamping jaws jointed to said rod, and means for opening and closing the same, means for conveying tabs to the jaws of the needles, the said means comprising a number of levers and spring clips mounted upon their ends and means for intermittently operating the same.

15. In a machine in which strips or tabs of cloth are fed to and passed through folds of a foundation canvas, the combination of a slotted table divided into longitudinal compartments, supports for the table for mounting it at an angle on the framework of the machine, sprocket wheels mounted on shafts, endless chains passing over said sprocket wheels, rods connecting the chains together, spiked blocks mounted upon said chains at intervals apart and arranged to work in the slots of the table, a tilting board fixed to the lower end of the inclined table, means for intermittently turning the board on to the spiked blocks for pressing a tab on to the spikes, means for raising one set of sprocket wheels and shafts and for tilting the bar, slotted framework, radial reciprocating levers jointed to the said framework, a rod for connecting said levers together, a plurality of double ended levers jointed to said rod, means for causing them to turn over during the movement of the radial arms, and spring clips for receiving the tabs jointed to the upper portion of the tilting levers for conveying the tabs from the spiked blocks to the needle jaws.

16. In a machine in which strips or tabs of cloth are fed to or passed through the folds of a foundation canvas, the combination of the framework, radial levers fulcrumed on said framework, a rod connecting the outer ends of said levers, means for intermittently swinging said levers, a plurality of double-ended levers pivoted on said rod, a lazy-tongs arrangement for connecting said levers together, means for operating said lazy-tongs and for reversing the position of said double-ended levers during the movement of the radial levers, a spring clip fixed on the upper end of each double-ended lever, means for feeding tabs to said clips, means for intermittently operating said feeding means, and a plurality of intermittently vertically reciprocating needle jaws adapted to pass through the folds of the

cloth and receive the tabs from said clips and carry the same through the folds.

17. In a machine in which strips or tabs of cloth are fed to and passed through folds of a foundation canvas, the combination of a framework having cam paths near the bottom of the same, a reciprocating bar mounted in slots in said frame, a plurality of needle jaws carried by said bar, means for opening and closing said needle jaws, an intermittently rotated winged roller around which the foundation canvas is carried, said roller having a plurality of recesses in each wing, a plurality of jaws pivoted on the

framework for clamping the foundation 15 canvas in a fold around the wing of the roller, a table for supporting the tabs, feeding means for carrying the tabs from the table, radial arms pivoted on the framework and provided with means for conveying tabs 20 from the feeding means to the needle jaws after they have penetrated a fold in the canvas, and means for returning the needle jaws to draw the tabs through said fold.

ROBERT WILLIAM SILVERSIDES.
